UNITED STATES PATENT OFFICE.

JOSEPH C. BELDEN AND ALBERT BEUTLER, OF CHICAGO, ILLINOIS,
ASSIGNORS TO BELDEN MANUFACTURING COMPANY, OF CHI-
CAGO, ILLINOIS, A CORPORATION OF ILLINOIS.

ATTACHMENT FOR DESK-TELEPHONES.

No. 818,602.

Specification of Letters Patent.

Patented April 24, 1906.

Application filed July 2, 1904. Serial No. 215,116.

To all whom it may concern:

Be it known that we, JOSEPH C. BELDEN and ALBERT BEUTLER, citizens of the United States of America, and residents of Chicago, county of Cook, and State of Illinois, have invented a new and useful Improvement in Attachments for Desk-Telephones, of which the following is a specification.

Our invention relates to an attachment for desk-telephones, the purpose of which is to carry a writing-pad upon which notes may be taken and memoranda made, this pad being always held in a convenient position to enable the telephone user to write thereupon.

Attachments for this purpose have been commonly applied to those telephone sets that are ordinarily mounted upon the wall and in some cases also to that class of telephones adapted to use upon desks or tables and commonly known as "desk-telephones." When applied to this latter class of telephones, writing-pads have been secured thereto in such manner as to afford an unstable base upon which to write, and, furthermore, appliances of this kind prior to our invention have been of such construction as to involve considerable expense in their manufacture, thus preventing their wide adoption.

It is the object of our invention to overcome these defects and also to secure a means of attachment to the desk-telephone stand which will be readily adjustable to various types of stands.

In the accompanying drawings, which illustrate our invention, Figure 1 is a complete view of a well-known type of desk-telephone to the stand of which our attachment is secured. Fig. 2 is a side view of our writing-pad attachment secured to the pedestal of the desk-stand, the remaining portions of the desk-stand being cut away for convenience in illustration. Fig. 3 is a view of the device of our invention less the paper-pad, its various parts being shown disassembled in order to more clearly indicate their respective functions. Fig. 4 is a view of the supporting-rod, upon which the plate for holding the pad is mounted. Fig. 5 is a sectional view showing the method of fastening the pad in place. Fig. 6 is a sectional view showing the method of attaching the pad-supporting plate to its supporting-arm.

Referring now to the several figures, A in-

dicates a supporting-plate for the writing-pad, and B a rod serving to support said plate. The left-hand end of the rod has a portion b bent in the arc of a circle, having approximately the same radius as the base of the desk-stand pedestal to which it is to be secured. Holes b' b' are drilled or punched in the straight portion of the rod on each side of the bent portion b, these holes being of such size as to freely admit the screws C C without engaging their threads.

D is a clamping member, having the portion d bent in the arc of a circle of similar radius to the bent portion b of the rod B. In the clamping member D are threaded holes d' d', adapted to register with the holes b' b' in the piece B and to be engaged by the threaded ends of the screws C C extending therethrough. By means of the clamping member D and the screws C C the supporting-rod B may be clamped upon a cylindrical portion of the base of the desk-stand pedestal, the screws serving to bind the bent portions of the rod B and the clamping member D into firm contact with said pedestal.

The plate A is secured to the free ends of the rod B primarily by means of the rivets E E E, (shown most clearly in Figs. 3 and 6,) these rivets passing through the holes b² b² b² of the rod B and through similar holes in the plate A. In order that the plate A may be made to assume a suitable angular position to facilitate writing upon it, the rod B is given a partial twist at the point b³, as most clearly shown in Figs. 3 and 4.

Two screw-threaded posts F project upwardly from the upper portion of the plate A, these posts engaging screw-threaded holes b⁴ b⁴ in the supporting-rod B and corresponding holes in the plate A. After being threaded into these holes through both the plate A and the rod B the ends of the posts F are upset, as at f, thus serving to rivet the posts firmly into the plate A and rod B. This method of construction is advantageous in that by using the combined thickness of the plate A and the rod B for support of the posts F a sufficient thickness of metal is secured to afford a rigid support for said posts. Such sufficient thickness is not found when the plate A alone is used to engage the posts F unless the plate A is made thicker than other requirements would dictate. In this

construction the portions of the screw-threaded rivet-posts F not screwed and riveted into the plate A and rod B form projecting members for the convenient attachment 5 of the writing-pad G.

G is a pad of paper of suitable form, this pad being perforated by circular holes near its upper edge of such size and such distance apart as to register with the two upright 10 posts F. The pad G when put in position upon the plate A is therefore held from lateral movement by posts F and is clamped in place by means of a binding-strip H and two thumb-nuts I, as most clearly shown in 15 the sectional view of Fig. 5. By thus securing the pad in place its individual sheets may be torn off, the binding-strip H serving as a guide in tearing the paper. The entire stub may be easily removed and another pad substituted when required. By fitting the writing-pad attachment to the base of the desk- 20 stand pedestal, as shown, a firm foundation upon which to write is secured, whereas with a pad supported from a point near the top of 25 the desk-stand pedestal, as in previous devices, a lack of rigidity results.

The method we use of clamping the device to the desk-stand pedestal is adaptable to different sizes of pedestal bases, as the 30 bent portion of the supporting-rod B and its auxiliary yoke or clamping member D are sufficiently flexible to permit considerable variation in the size of the cylinder they are adapted to clamp between them.

35 Having described our invention, what we desire to secure by Letters Patent is—

1. In an attachment for desk-telephones a plate for supporting a writing-pad, a rod supporting said plate and having its end bent 40 into the arc of a circle adapted to embrace a portion of the circumference of the pedestal of the desk-telephone, a yoke-piece bent into a similar arc, screws for clamping said rod and said yoke together around the base of 45 said pedestal, posts passing through said rod and said plate and riveted upon said rod and having projecting members, a writing-pad having perforations adapted to be engaged

by the projecting members of said posts, and means for holding said writing-pad upon said 50 posts, substantially as described.

2. In an attachment for desk-telephones, a plate for supporting a writing-pad, a rod riveted to said plate adapted to engage the pedestal of said desk-telephone, means for 55 clamping said rod into engagement with said pedestal, screw-threaded rivet-posts passing through said rod and said plate and riveted into said rod and said plate, a writing-pad, a binding-strip having perforations adapted 60 to be engaged by said rivet-posts, and nuts for said rivet-posts adapted with said binding-strip to clamp said pad upon said plate, substantially as described.

3. In combination with a telephone-desk 65 stand, a rod having a bent portion adapted to engage the pedestal of said stand, a yoke, also adapted to engage said pedestal, screws for clamping said rod and said yoke together around said pedestal, a writing-pad, a plate 70 for supporting said writing-pad riveted to said rod, posts for securing said writing-pad in place upon said plate, said posts passing through said plate and said rod and riveted thereto, a binding-strip also perforated to engage said posts and nuts adapted to engage screw-threads on said posts for clamping said binding-strip against said pad, substantially as described.

4. In an attachment for desk-telephones, a 80 rod, means for attaching said rod to a desk-telephone, a plate for supporting a writing-pad, rivets for holding said plate on said rod and having projecting members, a writing-pad, and clamping means associated with the 85 projecting members of said rivets and adapted to clamp said writing-pad upon said plate, substantially as described.

Signed by us at Chicago, county of Cook, State of Illinois, in the presence of two wit- 90 nesses.

JOSEPH C. BELDEN.
ALBERT BEUTLER.
